EDWARD WILHELM, OF BUFFALO, NEW YORK, ASSIGNOR TO A. W. FOX AND COMPANY, OF SAME PLACE.

Design No. 3,430, dated March 23, 1869.

DESIGN FOR A TRADE-MARK

The Schedule referred to in these Letters Patent and making part of the same.

To all whom it may concern:

Be it known that I, EDWARD WILHELM, assignor to Messrs. A. W. Fox & Co., of the city of Buffalo, in the county of Erie, and State of New York, have invented a new and original Design for a Trade-Mark; and I do hereby declare that the following is a full and exact description thereof, reference being had to the accompanying drawing, representing the same, forming part of this specification.

The design consists of a background of the form of a barrel, and representing such a vessel, with a representation of an apple, and one or more (preferably two) leaves attached to the stem thereof, arranged in the foreground, so as to cover the greater portion of the space occupied by the barrel.

It may be engraved, or be cut in a stencil-plate, the drawing representing the trade-mark as it appears when painted by means of a brush, and such stencil-plate, with the words "Trade" and "Mark" printed respectively on two leaves there shown.

The date of the patent I design to have marked on the figure of the apple, although I do not desire to confine myself to the marking of such date, or the words "Trade" and "Mark."

The trade-mark I consider as consisting of the two essential characteristics, of the figure of a barrel in the background, and the figure of an apple, with one or more leaves, occupying the foreground, the representation of letters, words, or figures thereon not being distinctive of the design.

What I claim as my invention, and desire to secure by Letters Patent, is—

The design for trade-mark, as herein shown and described.

EDWARD WILHELM.
